UNITED STATES PATENT OFFICE.

NATHAN SADOVSKY, OF SAN ANTONIO, TEXAS.

PRINTING-PRESS GRIPPER.

1,244,548.

Specification of Letters Patent. Patented Oct. 30, 1917.

Application filed November 10, 1916. Serial No. 130,600.

To all whom it may concern:

Be it known that I, NATHAN SADOVSKY, a citizen of the United States, residing at San Antonio, in the county of Bexar and State of Texas, have invented new and useful Printing-Press Grippers, of which the following is a specification.

The present invention appertains to printing presses, and aims to provide novel and improved gripping devices for a printing press, the improvements being adapted especially for use upon a printing press of the style disclosed in my Patent No. 1,088,732 granted March 3, 1914.

One of the objects of the invention is to provide a novel and improved paper gripping device carried by the type bed for carrying the paper to the rotary platen, the structure being comparatively simple and compact, as well as being thoroughly practical and efficient in operation.

Another object of the invention is the provision of a novel and improved gripping device carried by the rotary platen for taking the paper from the type and delivering it to the delivery belts, this construction also being simple and compact, as well as practical and efficacious.

The invention also includes novel means for operating the grippers of the two sets.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a plan view of the gripper device movable with and carried by the type bed.

Fig. 2 is a sectional view illustrating the gripping jaws of the type bed gripping device in position to receive the paper ready to grip the same, parts being removed.

Fig. 3 is an elevation, parts being removed and parts being shown in section, illustrating the two gripping devices in position ready to transfer the paper to the platen.

Fig. 4 is a fragmental elevation, similar

to Fig. 3 with additional parts removed, showing the parts advanced with the type bed gripping device open and the platen gripping device closed to carry the paper with the platen upwardly away from the bed.

Fig. 5 is a fragmental elevation illustrating the platen gripping device in position to deliver the paper from the platen to the delivery belts.

Fig. 6 is an enlarged detail view of the gears for operating the type bed gripping device.

Fig. 7 is a detail view, portions being shown in section, illustrating the platen gripping device in detail.

Fig. 8 is a sectional detail of the spring means for turning one of the rock shafts of the type bed gripping device.

The printing press with which the gripping devices are used embodies a type bed 1 movable in a circular or circuituous path, as disclosed in said patent, and carrying the type 2 upon which the paper 3 rests to move under the rotary platen 4.

The gripping device carried by the type bed 1 embodies forwardly projecting brackets or bearings 5 carried by the forward end of the bed 1 and in which a pair of spaced transverse rock shafts 6 and 7 are journaled in advance of the bed and below the surface of the type. Rearwardly projecting gripper jaws 8 are rotatable loosely upon the rear rock shaft 6, and have rubber bands 9 upon their free ends to prevent the slipping of the paper, said jaws 8 being movable downwardly from the surface of the type. The jaws 8 are provided with forwardly projecting toes 10 and rearwardly projecting arms 11 are secured to the rock shaft 7 and project rearwardly with their free ends bearing upon the toes 10. Leaf springs 12 are secured to the arms 11 and their free ends extend under the toes 10 to hold the toes and arms 11 in contact. It is evident that when the arms 11 are depressed, this depresses the toes 10 to raise the gripper jaws 8 to operative position.

There may be any suitable number of gripper jaws 8 which are spaced transversely of the type bed 1, and the jaws 8 are bifurcated to receive upper gripper jaws 13 secured rigidly to the shaft 6. The upper gripper jaws 13 are swingable forwardly and downwardly to open position, and are

swingable rearwardly and downwardly above the lower gripper jaws 8 for gripping the paper.

The gripper jaws 8 and 13 are operated by the oscillation of the rock shaft 6, which is accomplished by means of a pinion 14 keyed upon the shaft 6 and meshing with a spur gear 15 mounted for rotation in any suitable manner below the pinion 15. A spur gear 16 meshes with the spur gear 15 in rear of the same and is supported for rotation below the bed 1 in any suitable manner, the gears 15 and 16 being carried by the bed. A depending arm 17 is secured to the gear 15 and has an outstanding roller 18 movable over a series of tracks 19, and a depending arm 20 is secured to the gear 16 at the opposite side and has an outstanding roller 21 movable over a longitudinal series of tracks 22. The rollers 18 and 21 in moving over the respective tracks, serve to oscillate the shaft 6, as will hereinafter more fully appear, for operating the jaws 8 and 13.

A rearwardly projecting arm 23 is secured to the shaft 7 and carries an adjusting screw 24 for an expansion spring 25 disposed between said screw and a shelf 26 carried by the bed 1, whereby the spring 25 in expanding will raise the arm 23 to rock the shaft 7 so as to raise the arms 11.

In order to rock the shaft 7 to depress the arms 11 at the proper time, a depending arm 27 is secured to the shaft 7, and a collar 28 is secured upon the shaft 6 in rear of the arm 27 and has a radial lug 29. A stem 30 is slidably loosely through the arm 27 and a coiled wire expansion spring 31 upon said stem is confined between the arm 27 and a stop 32 carried by the stem 30 in rear of the arm 27, whereby the spring 31 tends to slide the stem 30 rearwardly. A spring 33 is connected to the stem 30 near its rear end to move the rear end of said stem up against the collar 28. When the shaft 6 is turned to swing the jaws 13 rearwardly and downwardly to gripping position, the collar 28 is turned to bring the lug 29 lowermost, so that it abuts against the rear end of the stem 30, thereby forcing said stem forwardly to compress the spring 31 which will press the arm 27 yieldably forward, whereby to rock the shaft 7 for depressing the arms 11, which will result in the toes 10 being depressed for raising the jaws 8 to gripping position to coöperate with the jaws 13, as seen in Fig. 3. When the shaft 6 is rotated to move the jaws 13 to open position, the lug 29 being moved rearwardly and upwardly will release the stem 30, so that the spring 31 will expand and thus permit the arm 27 to move rearwardly under the tension of the spring 25, thereby raising the arms 11 and the springs 12 in pressing the toes 10 upwardly will depress the jaws 8.

The gripping device carried by the platen 4 embodies a transverse rock shaft 34 journaled through certain spokes of the platen at the forward end thereof, and any suitable number of grippers are used upon the shaft 34. A rearwardly projecting arm 35 is secured to one end of the shaft 34 and carries a roller 36 working in a grooved or slotted cam 37 having the outer concentric portion 38 and the inner concentric portion 39. Each of the grippers embodies a block 40 having a circular opening 41 of larger diameter than the shaft 34 through which said shaft extends, and a shank 42 is secured to the block and projects radially outward, being provided at its outer end with a rearwardly curved gripper jaw 43 to press against the forward end of the arcuate platen 4. Within each opening 41, the shaft 34 carries a radially projecting key 44, which projects toward the center of the platen, and which contacts frictionally with the circular wall of the block 40 formed by the opening 41, as clearly seen by reference to Fig. 4. The block 40 has an extension 45 projecting radially outward opposite the key 44 and provided with a longitudinal bore 46 in which a coiled wire expansion spring 47 is disposed, the inner end of said spring pressing against the shaft 34 and its outer end bearing against a screw plug 48 threaded within the bore 46. The spring 47 tends to press the block 40 outwardly, thereby pressing it frictionally against the key 44. A coiled wire retractile spring 49 connects each shank 42 and the platen 4 whereby to pull the shank 42 rearwardly against the forward edge of the platen.

The type bed 1 is movable under the platen, the paper being carried from the bed by the platen to delivery belts 50 trained over pulleys 51 disposed at the top of the platen and superimposed to receive the paper therebetween from the platen which rotates in the direction of the arrows, counter clockwise, as illustrated in the drawings.

The operation of the mechanism is as follows:—

It is to be understood that the type bed and platen are operated in proper timed relation by suitable gearing provided for that purpose, as in the structure shown in the above mentioned patent. When the type bed 1 is moved under the inking rollers, the gripping device of the bed in the position illustrated in Fig. 2, the roller 21 moving upon a track 22 with the arm 20 in trailing position, the gear 16 having been rotated clockwise, as seen in Fig. 2, when the roller 21 moves onto the track 22, so as to rotate the gear 15 counter clockwise and the pinion 14 counter clockwise. The jaws 13 were therefore swung forwardly and downwardly when the roller 21 moved onto the track 22, and the shaft 6 being rotated, removed the

lug 29 from the stem 30, so that the arms 11 were raised and the jaws 8 depressed. The gripper jaws 8 and 13 were therefore ducked down to pass under the inking rollers without touching them. When the bed reaches the position illustrated in Fig. 2, to receive the sheet of paper 3 from the paper feeder, the roller 21 is ready to move off of the track 22, and the roller 19 is ready to move onto its track 19. Thus, as the paper 3 is fed over the jaws 8, the roller 20 leaves the track 22, and the roller 18 is stopped by the track 19, so that the continued movement of the bed 1 and the gear 15 will result in the arm 17 being swung rearwardly to move onto the track 19. Thus, the arm 17 rotates the gear 15 clockwise, as seen in Fig. 2, and the gear 16 is rotated counterclockwise to move the arm 20 forwardly, so that the arms 17 and 20 now assume the position illustrated in Fig. 3, with the arm 17 in trailing position on the track 19. Due to the swinging movement of the arm 17 and gear 15, the pinion 14 is rotated counter clockwise, as seen in Fig. 2, to swing the jaws 13 rearwardly and downwardly over the paper, and at the same time, the lug 29 in contact with the stem 30, will depress the arms 11, thereby to raise the jaws 8, so that the paper is gripped between the jaws 8 and 13, thereby carrying the paper with the type on which the paper rests. The bed and its gripping device move in this position to and under the platen, as illustrated in Fig. 3, and when the bed reaches this position, the roller 18 is ready to move off of its track 19, and the roller 21 is in position to move onto the next track 22, whereby to open the gripper jaws of the type bed. In this position of the parts, the gripper jaws 43 of the platen are immediately in advance of the forward edge of the paper. The shanks 42 are moved forwardly against the tension of the springs 49 for the reason which will appear herein-after, the keys 44 having been moved rearwardly by the outward movement of the roller 36 and arm 35. Now, as the roller 18 leaves the track 19, the roller 21 engages the track 22 and is retarded momentarily, thereby swinging the arm 20 rearwardly and rotating the gear 16 clockwise, as seen in Fig. 3, the arm 17 being swung forwardly to the position illustrated in Fig. 4. The gear 15 and pinion 14 are therefore rotated in the proper direction so that the jaws 13 are swung forwardly and downwardly, which results in the jaws 8 being depressed. At the time the jaws 8 and 13 open up, the roller 36 moves from the portion 38 of the cam 37 to the portion 39, thereby moving the roller 36 and arm 35 inwardly relative to the platen 4, and this will rock the shaft 34 clockwise, as seen in Figs. 3 and 4, relative to the platen. The keys 44 are there-

fore moved forwardly and in frictionally engaging the blocks 40, will swing said blocks to swing the shanks 42 rearwardly, thus moving the jaws 43 under the paper, and the keys 44 being moved inwardly, will force the blocks 40 inwardly thereby moving the jaws 43 inwardly against the platen to grip the paper as the jaws 8 and 13 separate. The parts are now in the position illustrated in Fig. 4, the paper being carried from the type by the platen. The paper is delivered from the platen at the top thereof, since when the forward edge of the paper reaches the pulleys 51, the roller 36 moves from the portion 39 to the portion 38 of the cam 37, thereby swinging the arm 35 outwardly relative to the platen, and the keys 44 in frictionally engaging the blocks 40, will swing said blocks whereby to swing the shanks forwardly away from the platen. The jaws 43 are therefore moved forwardly away from the paper as the paper moves between the belts 50, and the keys 44 being moved rearwardly, are moved outwardly, whereby the springs 47 press the blocks 40 outwardly to move the jaws 43 away from the platen. This removes the jaws 43 from the paper as it moves between the belts 50, and the jaws 43 remain in this position in their downward movement to grip the next sheet of paper as above described.

With the present mechanism, a series of type beds can move in succession under a series of inking rollers (not shown) and platens 4, as will be obvious especially by referring to the aforementioned patent. It will also be apparent that a suitable number of tracks 19 and 20 are employed, according to the number of platens, etc.

Having thus described the invention, what is claimed as new is:

1. In a printing press, the combination with a movable member, of a paper gripping device carried by said member embodying gripper jaws, a pair of oppositely swinging arms carried by said member for operating said jaws, and tracks upon which said arms are adapted to alternately ride for opening and closing the jaws.

2. In a printing press, the combination with a movable member, of a paper gripping device carried by said member including gripper jaws, an oscillatory shaft for operating said jaws, a pair of intermeshing gears connected to said shaft for oscillating in different directions, arms carried by said gears to operate in opposite directions, and tracks upon which the arms are adapted to ride alternately for oscillating said gears and shaft.

3. In a printing press, the combination with a movable member, of a gripping device carried by said member including an oscillatory shaft, gripper jaws operated by said shaft, a pinion carried by the shaft, a

gear meshing with said pinion, a second gear meshing with the aforesaid gear, depending arms carried by the gears, and tracks over which said arms are adapted to trail for oscillating the gears and shaft in opposite directions.

4. A gripping device for printing presses embodying a gripper jaw arranged to swing through a relatively large arc into and out of gripping position, a second gripper jaw swingable through a small arc and coöperable with the aforesaid jaw, means for oscillating the first mentioned jaw, and means for oscillating the second mentioned gripper jaw through its arc when the first mentioned jaw completes and starts its movements toward and away from the second mentioned jaw, respectively.

5. A gripping device for printing presses embodying an oscillatory shaft, a gripper jaw secured upon said shaft, a second gripper jaw mounted loosely upon said shaft to coöperate with the aforesaid jaw, and means operated by the oscillation of said shaft for operating the second mentioned jaw whereby the two jaws swing toward and away from one another into and out of gripping position.

6. A gripping device for printing presses embodying an oscillatory shaft, a gripper jaw secured thereon, a second oscillatory shaft, a second oscillatory gripper jaw mounted loosely upon the first mentioned shaft and operatively connected with the second mentioned shaft, and means for oscillating the second mentioned shaft after the first mentioned shaft has been turned to move the first mentioned jaw to gripping position whereby to swing the second mentioned jaw toward the first mentioned jaw to gripping position.

7. A gripping device for printing presses embodying an oscillatory shaft, a gripper jaw secured thereon, a second gripper jaw mounted loosely upon said shaft, a second oscillatory shaft having an arm, the second mentioned jaw having a portion engaged by said arm, and means operatively connecting said shafts whereby when the first mentioned shaft is turned to move the first mentioned jaw to gripping position, the second mentioned shaft is operated to swing said arm and thereby swing the second mentioned jaw to gripping position.

8. A gripping device for printing presses embodying an oscillatory shaft, a gripper jaw secured thereon, a second gripper jaw mounted loosely upon said shaft and coöperable with the aforesaid jaw, a second oscillatory shaft, an arm carried by the second mentioned shaft, the second mentioned jaw having a toe upon which said arm bears, spring means for holding said arm and toe in contact, and an operative connection between the shafts whereby the second men-

tioned shaft is oscillated after the first mentioned shaft is turned a certain amount.

9. A gripping device for printing presses embodying an oscillatory shaft, a gripper jaw secured thereto, a second gripper jaw mounted loosely upon said shaft, a second oscillatory shaft connected to the second mentioned jaw to operate it, and means operatively connecting the shafts for yieldably oscillating the second mentioned shaft after the first mentioned shaft has been turned a certain amount.

10. A gripping device for printing presses embodying an oscillatory shaft, a gripper jaw secured thereto, a second gripper jaw mounted loosely upon said shaft, a second oscillatory shaft operatively connected with the second mentioned jaw to oscillate it, an arm carried by the second mentioned shaft, a stem slidable loosely through said arm, spring means for moving said arm with said stem, spring means for swinging said stem toward the first mentioned shaft, and a portion carried by the first mentioned shaft to abut against and move said stem when the first mentioned shaft is turned a certain amount.

11. A gripping device for printing presses embodying an oscillatory shaft, a gripper jaw secured thereto, a second gripper jaw mounted loosely upon said shaft, a second oscillatory shaft, an arm carried by the second mentioned shaft, a toe carried by the second mentioned jaw upon which said arm bears, spring means for holding said arm and toe in contact, a collar carried by the first mentioned shaft and having a lug, a second arm carried by the second mentioned shaft, a stem slidable loosely through the second mentioned arm, spring means for moving the second mentioned arm with the stem, and spring means for holding the stem against said collar for the abutment of said lug thereagainst when the first mentioned shaft is turned a certain amount.

12. A gripping device for printing presses embodying a gripper jaw swingable through a relatively large arc, a second gripper jaw coöperable therewith and swingable through a small arc, means for oscillating the first mentioned jaw, and means for yieldably moving the second mentioned jaw toward the first mentioned jaw when the first mentioned jaw has moved a certain amount toward the second mentioned jaw.

13. In a printing press, the combination with a rotary platen, of a rock shaft carried thereby, means for oscillating the rock shaft during the rotation of the platen, a member having an opening through which said shaft extends, a gripper jaw carried by said member, spring means for moving said member outwardly, and means carried by said shaft and engaging said member to oscillate it and said jaw.

14. In a printing press, the combination with a rotary platen, of a rock shaft carried by said platen, a block having an opening through which said shaft extends, an 5 outwardly extending shank carried by the block and having a rearwardly curved gripper jaw at its outer end coöperable with the platen, spring means tending to move said jaw rearwardly, spring means carried 10 by said block for moving it outwardly relative to said shaft, a key carried by said shaft

projecting inwardly and engageable with the walls of said opening for oscillating said block with said shaft, and means for oscillating said shaft as the platen rotates. 15

In testimony that I claim the foregoing as my own, I have hereto affixed my signature in the presence of two witnesses.

NATHAN SADOVSKY.
